UNITED STATES PATENT OFFICE.

ROBERT H. SHARP, OF CHICAGO, ILLINOIS.

VANITY-CASE.

1,353,281.

Specification of Letters Patent. Patented Sept. 21, 1920.

Application filed June 14, 1920. Serial No. 388,959.

To all whom it may concern:

Be it known that I, ROBERT H. SHARP, a citizen of the United States, residing at Chicago, in the county of Cook and State of Illinois, have invented certain new and useful Improvements in Vanity-Cases, of which the following is a specification, reference being had to the accompanying drawings, and to the reference characters marked thereon, which form a part of this specification.

This invention relates to toilet articles and containers therefor, and consists in the matters herein illustrated, described and claimed.

One of the objects of the present invention is to provide a desired quantity of rouge in compressed cake or tablet form, and a desired quantity of face powder preferably also in cake form, and a suitable container for the two, which latter shall be provided with a mirror and with a rouge and a powder puff, thereby producing an efficient, neat and relatively inexpensive toilet article.

Another object is to provide a toilet article of relatively small size, with means for replenishing the supply of powder, one or more times; a desideratum since a cake of rouge will normally outlast a very much larger volume of powder.

Another object is to so arrange the article as a whole that, while containing rouge and face powder, puffs, and a mirror, the size shall be of small dimensions, whereby the user may the more conveniently carry it in her hand bag or purse.

35 In the accompanying drawings:

Figure 1 is a view in side elevation, of a box containing my invention.

Fig. 2 is a central vertical sectional view of the same.

40 Fig. 3 is a bottom plan view of the same.

Fig. 4 is a view showing all of the parts detached.

The box illustrated comprises a main or bottom member A and a removable closure or top member B. These are preferably of metal, pressed or worked up into the shape shown. The bottom A has a cylindrical body portion 1 provided at its lower end with an inturned annular flange 2, and near its upper margin, with an outwardly projecting annular bead or shoulder 3. The top member B is, preferably, a rounded or convexed disk 4 provided with a downwardly extending annular flange 5 of an internal diameter to permit it to have a nice fit over that portion of the body 1 that extends above

the bead or shoulder 3. This bead 3 acts as a stop for the lower margin of the flange 5 when the members A and B are brought together.

Within the body portion 1 of the bottom member A I place a looking glass or disk C. This may be of any suitable material, such for example as a glass mirror. The disk C is preferably of the diameter of the interior 65 of the body 1 and rests upon the inside of the flange 2 with its reflecting surface visible through the flange aperture when the box is inverted. A washer 6, of paper or other suitable material, may be placed upon the 70 disk C to protect the reflecting medium thereon. A cup, D, is provided, having a bottom 7 and an annular flange 8, the latter of such external diameter as to fit snugly but removably within the body 1. The bottom 75 8 will rest upon the disk C or upon the protecting washer 6 when the latter is used, thus holding the disk in place. Within the cup D is placed a cake of face powder P, which I usually prefer to mold upon a shallow 80 flanged bottom plate 9 as shown. This bottom plate 9 will, in use, rest upon the bottom 7 of the cup D. A powder puff Q, of any suitable material, will rest upon the face powder cake P.

85 The cake of rouge or color R is placed upon a shallow, flanged bottom plate 10 and is placed within the body 5 of the top member B. A shallow, flanged ring member S retains the rouge cake R and its 90 plate 10 within the member B, as shown. A disk T of felt or other suitable material, will be placed upon the cake R.

The diameter of the ring S will be such as to insure a very close fit within the member B; thus locking the rouge cake R in place, the convex portion of which will project through the opening in the annular inverted flange 11 of the retaining ring S.

When the several parts shown in Fig. 4 are assembled, they will be in the position illustrated in the sectional view Fig. 2. The powder cake P will become exhausted in use much sooner than the relatively small rouge cake R, and hence I provide for the easy removal of the cup D from the bottom member A, so that a new powder cake P and its container D, may be exchanged for the first mentioned cup D and the used-up powder cake.

The device illustrated affords a small and very useful toilet article. The rouge case

R will, preferably, include talc in powdered form to which a suitable coloring matter has been added, and then pressed into any desired tablet or other form. The 5 powder cake P will be prepared in a familiar manner and will, preferably, be of larger volume than the rouge cake. The removability of the cup D and its plate 9, when the powder cake is exhausted, and 10 the substitution in its place of a similar container D and plate 9 and new powder cake, will be found of great convenience and value. It will be understood that I may dispense with the plate 9 and press the 15 powder directly in the cup D.

I claim as my invention:

1. A toilet article including in combination a two part container, the lower member of which having an inturned flanged ring 20 and a mirror within said lower member resting upon said ring and visible therethrough, a washer upon the back of the mirror, a removable cup within the washer and face powder within the cup, and a cake 25 of rouge upon a backing plate located within the upper member of the container, a flanged ring within the upper member to retain the rouge cake in place, a rouge and powder puff within the container separating 30 the rouge from the powder, and coöperating means for removably uniting the two parts of the container.

2. A toilet article container comprising a cylindrical open bottom lower member and

a flanged top member adapted to fit upon 65 the lower member, an annular bead formed, on the lower member for engagement with, the lower edge of the top member, a mirror within and visible through the open bottom of the lower member, a washer upon the 40 back of the mirror, a cup member removably positioned within the cylindrical part of the lower member, adapted to hold the mirror in position and also to receive and hold a toilet preparation, in combination 45 with a toilet preparation within the top member and a flanged ring washer to hold the toilet preparation within said top member.

3. In a toilet article container, the combination with a cylindrical open bottom member and a cup shaped closure member adapted for operative engagement with each other, of means for securing a toilet article within the latter, a mirror within the former and visible through said open bottom, and a toilet preparation cup removably positioned within said lower member and adapted to hold the mirror in place.

In testimony, that I, claim the foregoing 60 as my invention I affix my signature, in the presence of two witnesses, this 11th day of June, 1920.

ROBERT H. SHARP.
